UNITED STATES PATENT OFFICE

2,605,025

FILLING MACHINE WITH CONTROLLED DRAWBACK

Frank J. Cozzoli, Plainfield, N. J.

Application May 4, 1949, Serial No. 91,305

7 Claims. (Cl. 222—375)

1

The present invention relates to ampul and the like, filling machines and is concerned more particularly with an improvement designed to eliminate drop formation at the end of the filling needle. A primary aim of the invention is to enable a user to fill an ampul or other slender throated tube with a liquid preparation without wetting the tube neck. Non-wetting is especially important in the case of ampuls and tubes that are subsequent to filling, sealed by the application of heat. Whether the seal is made by drawing off the tip of a tube or by sealing the tip, objectionable charring occurs if the interior of the tube neck in the region of the seal has been wetted by the preparation.

A further aim of the invention is to prevent drop formation on the needle end in a manner that lends itself adaptable to large gauge as well as small gauge filling needles. It has been observed that the drop that tends to form on the needle end at the completion of a filling cycle bears a relation to the unit quantity dispensed, size of needle, and viscosity of the medium being dispensed and to meet the various conditions arising in the field this invention aims to provide a filling machine embodying a drop eliminator that is operative over the entire capacity range of the filling machine to prevent drop formation under all normal conditions of use.

The instant invention is in part a continuation of my application Ser. No. 62,121, filed November 26, 1948, now Patent No. 2,518,870, disclosing a filling machine having a reciprocating piston and cylinder type of measuring unit, slide valve controlled, and a variable speed drive means for actuating the measuring unit and its valve in fixed timed relation. The present invention is disclosed in connection with a similar machine embodying a measuring unit, valve means therefore and actuating means, but in which it has now been made possible to vary the timing of valve movement relative to measuring and dispensing cycles in a manner so as to effect a selected regression of the flow in the needle on completion of the filling cycle best suited to the character of the medium used, the needle size, and the unit quantity delivered. With the aid of this invention, the user of the filling machine is provided means operable over a wide range of different conditions to prevent drop formation on the filling needle whereby wetting of tube throats and the objectionable consequences thereof is avoided.

Other objects and advantages will be in part indicated in the following description and in part rendered apparent therefrom in connection with the annexed drawings.

2

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

10 Fig. 1 of the drawings is a side view of a filling machine embodying the invention, shown partly in section better to illustrate its constructional features.

15 Fig. 2 is a front view of portions of the measuring unit drive and portions of the valve actuating mechanism.

Fig. 3 is a plan view of a preferred form of slide valve.

20 Fig. 4 is a sectional view, on a vertical plane of the valve.

Fig. 5 is a front view, partly in section of a combined crank and valve actuating cam.

25 Fig. 6 is a projected view of Fig. 5, and Fig. 7 is a plan view of Fig. 5.

With reference more particularly to Fig. 1 of the drawing the invention is disclosed in connection with a filling machine that comprises essentially a base member 10, a front panel 11, a measuring unit 12, a control valve 13, a filling needle 14 and a variable speed drive motor 15 for operating the measuring unit and valve whereby to effect pump action. The motor 15 is of commercial construction and equipped with a geared reducer, a speed control handle 16, a resistor and lead cord (not shown) in a known manner.

30 The motor shaft 15a extends forward and carries a combined crank and cam member 17 to which one end of a connecting rod 18 is eccentrically pivoted as at 18a. The other end of the connecting rod is pivoted to the free end of an oscillatable lever 19 which in turn is fixedly mounted upon a shaft 20 journaled in bearings provided by the front panel 11. The shaft 20 extends through the panel and carries an arc-shaped lever 21 that operates the measuring unit 12.

35 The measuring unit, in the instant embodiment of the invention, is in the form of a piston 22 and a cylinder 23 arranged substantially upon a vertical axis. The cylinder is the lower member, preferably, and is pivotally connected to the arcuate lever 21 by means of a pintle yoke 24. The yoke is adapted for adjustment radially on the lever and is clamped in the selected position by a clamp screw 25. As the lever 21 is oscillated

the pintle yoke is raised and lowered and its magnitude of swing is determined by the radial position of the yoke on the lever 21. If the yoke is positioned in coincidence with the pivot 28, the stroke imparted to the cylinder is zero, and the more outwardly the yoke is positioned, the greater is the stroke imparted to the cylinder.

The piston 22 of the measuring unit is formed with a hollow stem, indicated in Fig. 1, through which the fluid is drawn in and expelled from the cylinder chamber during the reciprocatory motions of the cylinder. The upper end of the piston is screw threaded into the body part 13a of the valve 13. As illustrated more clearly in Figs. 3 and 4 the valve body 13a is mounted upon an oscillatable shaft 26 journaled in the panel 11, and is provided with three separate fluid passages a, b, and c, the passage a leads to the filling needle via connections d and e; the passage c communicates with a supply conduit s; and the passage b communicates with the interior of the cylinder 23 by way of the hollow piston. The three ports a, b, c, are normally isolated from one another, but communication is established between ports a and b, and between b and c, in alternation, by means of an elongated bridging port f formed in the upper slide plate 13b. In Fig. 4 the slide plate is in its rearmost position wherein the cylinder is connected with the supply conduit s, in which position, fluid is about to be drawn into the cylinder, whereas in Fig. 1, the slide plate is in its forward position wherein the cylinder is in communication with the delivery conduits d and e and the fluid about to be expelled from the cylinder passes through the needle 14 to the interior of the ampul or tube to be filled.

The valve slide 13b is spring pressed against the body part 13a and is intermittently actuated in timed relation with the reciprocatory movements of the measuring unit. The slide actuating mechanism includes a shiftable spool member 30 that is slidable on the shaft 26, a connection bar 31 that transmits the endwise motion of the spool 30 to the valve slide, a two-armed medially pivoted lever 32 that forks the spool 30, and the aforementioned crank-cam 17 which is arranged to rock the lever 32 intermittently.

As illustrated more clearly in Figs. 5, 6, and 7, the crank-cam 17 is formed with two diametrically opposite and axially opposite half-flanges 17a and 17b. The adjacent leading and trailing ends of the half-flanges are correspondingly beveled to form inclined channels 17c and 17d constructed and arranged to engage and shift the lower end of the valve lever 32 from one effective position to another in alternation. To minimize wear the lever 32 is provided with a cam follower roller 32a at its cam engaging end.

It will be observed in Fig. 1 that the lever 32 is pivoted at 32b to one arm of a bell crank lever 35 which in turn is pivotally supported, as at 35a, on the panel 11. The other arm of the bell crank lever 35 is provided with a cross pin 36, constructed in the form of a nut, for an adjusting screw 37. The bell crank is also recessed to receive a compression spring 38 arranged to react against the panel 11 and normally tends to move the bell crank 35 counterclockwise about its pivot 35a. The head of the screw 37 abuts the front of the panel 11, and fixes the position of the bell crank lever. As the screw 37 is turned the threaded pin 36 is caused to travel in or out along the screw and in so doing the arm that carries the lever 32 is caused to raise and lower 75 from the center of rotation of the cam or less outward

accordingly. A pair of jam nuts 37a on the screw 37 limits the travel in one direction, and the panel itself limits the movement of the bell crank in the opposite direction.

The purpose of raising and lowering the lever 32 is to provide controllable means for preventing drop formation on the needle under different conditions, and is effected with the present invention by varying the phase relations of the shifting movements of the valve and the reciprocatory movements of the piston and cylinder elements. With reference to Figs. 2, 5-7, one of the oppositely disposed follower channels 17d in the cam 17 is offset from a radial plane that intersects the crank axis 18a and the other cam channel 17c is substantially in that plane. The cam channel 17c is arranged to actuate the valve lever and to shift the valve from its rearmost position (Fig. 4) to its forward position (Fig. 2) substantially coincidently with the completion of the intake stroke of the measuring unit so that the quantity entrained in the cylinder will discharge through the delivery channels and filling needle on the discharge (or upward) stroke of the cylinder. The cam channel 17d, however, is circumferentially offset from the aforesaid diametral plane, in a direction that causes the valve to be shifted from a delivery position (Fig. 2) to its intake position (Fig. 4) a short interval of time subsequent to the start of the intake stroke of the measuring unit. With such an arrangement, the valve is "late" in relation to the intake stroke and "on time" in relation to the discharge stroke.

This delaying of valve shift at the end of the delivery and at the start of the intake cycle, effects a drawback of a fixed quantity from interior of the needle and effectively prevents drop formation at its end. However, if the needle is large bored, the regress of fluid will be inconsequential, if the needle is small bored the same quantity drawn back will be considerable and air may be drawn into the cylinder. Still again if the stroke setting for a selected volumetric displacement is small and the yoke 24 positioned relatively close the axis of the lever 21, the drawback becomes substantially nothing as compared with the drawback produced when the yoke is outwardly positioned on the lever for a greater quantity displacement.

In an attempt to obtain a controlled drawback under all conditions this invention proposes a means for varying the "lateness" of valve shift occurring at the end of the delivery cycle to the end of obtaining a drawback that is no more than adequate to bring into the needle end the final drop of liquid that ordinarily tends to hang there. By so removing the droplet, the needle may be caused to enter and leave the narrow neck of an ampul without danger of wetting the sides. In attaining this end, it is proposed to superpose on cam channel 17d a further configuration operative to lengthen the dwell period of the valve to a greater or lesser degree depending upon the requirements. Fig. 5 illustrates the further configuration given to the beveled leading end of the flange 17a and which is formed by slanting the face 17e thereof both circumferentially and axially rearwardly. Accordingly by raising or lowering the effective position of the valve shifting lever 32, the follower roller 32a is caused to rest in a position as to be engaged by the cam face 17e along a line more outward from the center of rotation of the cam or less outward

lever is such that the follower is acted upon by the inner portion of the face 17e, the valve will be shifted sooner than if the lever occupied a more elevated position and the follower was engaged by a more outwardly located portion of the compoundly slanted face 17e of the cam 17. Raising or lowering of the lever 32 has no effect upon its operative connection with the slide shifting spool 30 for the reason that the walls thereof that contain the forked end of lever 32 are parallel and perpendicular to the axis of the supporting shaft 26.

It will be further observed that the follower channel 17c at the opposite side of the cam 17 is formed, as above indicated, with its camming surfaces at opposite sides of a substantially diametral plane and the raising or lowering of the follower roller thereinto has no effect upon the timeliness of shift of the slide valve occurring at the end of the intake stroke of the measuring unit.

With the present invention a simple means is provided for eliminating drop formation and for controlling the amount of drawback in any of a wide range of variable conditions to the end of maintaining a dry needle so that the necks of small vials, tubes, ampuls and like containers are not made wet by the passing of the filling needle therethrough.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A means for eliminating drop formation on the end of a needle of a filling machine having a measuring unit, valve means operative to connect the measuring unit alternately with a bulk supply and with the filling needle, and means for actuating the measuring unit, comprising in combination means for actuating the valve in timed relation with the operation of the measuring unit, said means including a pivoted lever connected to operate the valve, and cam means operative to actuate said lever about its pivot alternately to two effective positions, and means operable to delay the movement of the lever from one of its positions until the measuring unit has been actuated a preselected unit of measure in a fluid intake direction, said last named means comprising a support for the pivot of said pivoted lever shiftable relative to said cam, and means operable to shift said support and thereby said pivoted lever relative to said cam means thereby to cause said lever to respond to the action of a selected portion of said cam.

2. A means for eliminating drop formation on the end of a needle of a filling machine embodying a measuring unit, valve means having two effective positions operative to connect the measuring unit alternately with a bulk supply and with the filling needle, and means for actuating the measuring unit, comprising in combination means for actuating the valve in timed relation with the operation of the measuring unit, said means including a shiftable member operatively

connected with a movable part of the valve and a relatively wide faced asymmetrical cam element operative to actuate said shiftable member alternately to two effective positions corresponding to the two effective positions of the movable part of the valve, and means to shift said shiftable member relative to the face of said cam element thereby to change the time of movement of the valve from one of its positions to the other until the measuring unit has been actuated a preselected quantitative amount.

3. A dispensing machine of the character described comprising in combination a variable displacement liquid measuring means, valve means associated therewith operative to connect the measuring means alternately with a source of liquid to be dispensed and with the filling needle of the machine, means for actuating said measuring means, means for actuating said valve in timed relation with the operation of the measuring means whereby to cause liquid to enter and to be discharged from the measuring means, said last mentioned means comprising a rotary cam element having at least one effective follower-engaging region slanted in plane extending transverse the axis of the cam, and a cooperating adjustable follower element engageable by said cam and operatively connected to actuate the valve means, and means for shifting the said follower relative to said cam whereby to vary the timing of the actuation of the valve relative to the measuring and dispensing cycles of said measuring means.

4. A filling machine comprising in combination a variable displacement measuring pump unit, valve means normally operative to connect said pump unit with a supply conduit on an intake stroke of the pump and with a discharge conduit on a discharge stroke of the pump, means including a cam element for actuating said pump unit and said valve means in synchronism whereby to cause said pump to receive and expel a predetermined quantity of liquid medium, and manually controlled means for varying the timing of the actuation of said valve means with relation to the timing of the actuation of said pump unit, comprising a shiftable cam follower member adapted to track said cam and screw means connected to shift said follower from one effective position to another effective position relative to said cam.

5. A filling machine including a pump and a filling needle adapted to deliver fluid discharged by the pump into a container combining, means connected to actuate said pump in a pump intake direction and in a pump discharge direction, valve means for the pump, means for actuating said valve means intermittently in substantial coincidence with the changes in direction of actuation of the pump, comprising relatively shiftable cam and cam follower elements operative to effect movement of the said valve from one effective position to another effective position and means operable selectively to shift one of said elements relative to the other so as to effect an increase and decrease in the dwell periods of the valve means whereby to cause said pump unit to remain connected with said discharge conduit for a period in excess of the period it is connected with the intake conduit.

6. A filling machine comprising in combination a variable displacement reciprocable pump unit, valve means normally operative to connect said pump unit with a supply conduit on an intake stroke of the pump and with a discharge
